PHOTOGRAPHIC TYPE COMPOSING

Edmond Uher, Munich, Germany, assignor to
Uhertype Aktiengesellschaft, Glarus, Switzerland, a corporation of Switzerland

Application January 17, 1935, Serial No. 2,155
In Germany January 23, 1934

6 Claims. (Cl. 95—4.5)

My invention relates to a method of and means for photographic type composing, where a definite photographic representation of pages of type matter to be reproduced directly or in the form 5 of a printing surface in its made up or page form is produced by photographing step by step type matter in the form of lines or like letterpress units ready for reproduction, gauging means arranged according to a system of two co-ordinates 10 being provided for locating the letterpress units accurately in correct relationship with respect to one another during their photographic reproduction to produce the representation of the printing surface in its made up form.

15 In a known process the letterpress units are provided on individual loose carriers, each carrier being provided with gauging means arranged according to a definite system of two co-ordinates, said carriers being applied to a support 20 having corresponding gauging means, so as to locate the carriers accurately on the said support according to the said two co-ordinates. Such a procedure allows of unlimited flexibility and variations of the type matter but suffers from the 25 disadvantage that owing to the enormous quantity of loose separate carriers for the letterpress units, the provision of mechanical collecting means is necessary in order that they can be preliminarily arranged and correctly handled, and 30 that the direct carriers of the type matter necessitate relatively large blank surfaces, so that the waste of material is very heavy.

It has also been proposed to produce printing surface by attaching in parallel columns to a 35 glass-plate film strips bearing representations of the type matter, the attachment being effected by engagement of perforations in the edges of the film strips with pins fast on the plate, and photographing the film strips in one operation. The 40 columns of type matter on the film strips must have the same line spacing and the same column margins as those of the page to be produced, so that with the very small spaces between the 45 lines or the columns which will in most cases occur, it is practically impossible to handle and divide up the type matter without damaging it. While faulty parts may be cut out and replaced by correct pieces, the separate lines can themselves no longer be adjusted and where, as is 50 generally the case, any correction necessitates a complete rearrangement, since in most cases, instead of a single line, several lines may have to be inserted or a certain number of lines may have to be replaced by a smaller number of lines, 55 the length of the already mounted strip would in

each case have to be altered. To this must be added the drawback that in the carrying out of the photographic reproduction, it is not possible to alter the degree of enlargement locally and that the attachment means have to be photographed along with the type matter. Furthermore, the pins and perforations for attaching the film strips to the glass plate make no allowance for any possible extension of the film strip.

The present invention has for its object to 10 eliminate the mechanical assembling of the lines into column form and to reduce the waste of film or other material on which the lines of type matter are provided while at the same time preserving the flexibility of the process and permitting 15 of correction, interposition, alteration, embellishment, and so on, in any desired manner. With this object in view the invention consists in a photographic type composing process in which the final photographic representation of the type 20 matter in its made up or page form is produced by photographing step by step type matter in the form of lines or like letterpress units ready for reproduction, provided directly on a common carrier in groups one below the other with a constant optional line spacing to form a roughly set 25 up column, the common carrier being provided with gauging means arranged according to a system of two co-ordinates for each of the letterpress units for accurately locating the letterpress 30 units in correct relationship with respect to one another during their photographic reproduction to produce the representation of the printing surface in its made up form, the said gauging means being arranged in alignment one below 35 the other in the direction of the one co-ordinate and being parallel to one another in the direction of the other co-ordinate.

The lack of flexibility which might otherwise be imposed on the process because of the letterpress units being preliminarily arranged in column form is thus avoided due to two reasons. If the letterpress units be aligned in the exposing position during the photographic reproduction with the aid of the gauging means provided 40 on the common carrier for each separate letterpress unit, the photographic reproduction can be effected step by step with a similar freedom and with the same accuracy as if the letterpress units were provided on separate carriers assembled on a support, all that need be done according to the present invention being to advance the common carrier of the column of letterpress units so as to bring the successive units into the operative position, each unit being located by means 45 50 55 55

of its gauging means independently of the gauging means for the other units, so that the carrier can have sufficient freedom of motion to align or set itself always exclusively by the appropriate 5 gauging means.

The distance between the lines of type matter on the common carrier, may be different from that of the lines of the final photographic reproduction, a constant spacing between the lines of 10 the rough column being preferably selected, which entails no waste of material, such as film for the carrier but which is wide enough to enable the carrier to be easily severed between the lines and pieced together. The piecing together can be effected 15 without any detriment to typographical accuracy if the places where the carrier is pieced together are located by means of the gauging means of a number of adjacent letterpress units.

If the letterpress units are normally to be reproduced 20 in the same small size of type while only in certain places is the type required to be of larger size, which is effected by varying the scale of reproduction while the page is being photographically produced, the invention has the advantage 25 that the waste of film or other material forming the common carrier is again reduced and that the gauging means of the carriers can be standardized. This is accompanied by the additional and, by no means unimportant advantage, 30 particularly in the case of carriers comprising light-sensitive film bands on which the letterpress units are set up photographically, that the gauging means, such as gauge holes for the successive letterpress units in the column can be provided 35 beforehand in the carriers before producing on them the letterpress units. In this way the compositor is relieved of the work of perforating the film and the gauge holes can be set out beforehand with the greatest accuracy during the manufacture of the film.

As will hereinafter be more fully explained, 40 the size of the free margins of the column of letterpress units can be independent of the size of the margins of the photographic representation of the type matter in its made up page form, so that the size of margin for the column of letterpress units can be chosen which will be most convenient for the handling of the letterpress units.

The accompanying drawings show diagrammatically 45 several examples of different means for carrying out the process according to this invention. Fig. 1 is a view of part of a column of letterpress units on a common carrier on an enlarged scale. Figs. 2 to 7 and 10 are fragmentary views 50 of different letterpress unit carriers. Fig. 8 is a longitudinal section through a portion of a splicing table. Fig. 9 is a longitudinal section 55 through part of a feed device for guiding the letterpress unit carrier during the photographic reproduction of the type matter. Fig. 10 is a view of a normal continuous column broken apart. Figs. 11 to 16 are views of different photographic representations of the type matter in its made up form.

According to Fig. 1 the letterpress units 1, 60 which are photographs of lines are provided on a film band 2. The gauging means of the first line are the round hole 3 and the elongated hole 4, in each of which enters a round pin 5. The 65 centres of the two holes 3, 4 are on a straight line, the base line S and the left hand marginal line R being in each case disposed at fixed distances X and Y from these centres. Thus the 70 unit 1 is located perfectly accurately according to two co-ordinates, so that for instance from

the position of the two holes 3, 4 it is possible when using any given reproducing camera to ensure that the images of the letterpress units will be successively projected with certainty in the correct position on the light-sensitive carrier of the photographic representation of the type matter in its made up form. The hole 4 is an elongated hole which allows the film band 2 to expand in width without affecting the accuracy of adjustment. 10

The second line has as gauging means two square holes 6 in which the four-cornered pins 7 and 8 engage. The holes 6 follow at a pitch distance T after the two holes 3, 4 and the position of the second line image is adjusted with respect to the centres of the two holes 6 also in accordance with the two fixed distances X and Y. The film band 2 is in this case again engaged rigidly only with respect to the left hand gauge hole 6, while on the right-hand side it is held yielding 20 in the direction of the common centre line of the two gauge holes 6 through the hole 8 being made narrower than the pin 6 in this direction, that is to say in the direction of the length of the line or width of the type matter. Thus the 25 film band 2 is free to expand in width, even when both gauge holes are of the same size. It may also be mentioned that such an expansion can be provided for by the gauge holes at the side of the column where the film band is free to expand and 30 being engaged by a springloaded finger or the like which seeks to spread the pairs of gauge holes in question gently apart and thereby tighten the band.

Any number of units 1 and corresponding gauge 35 hole 3, 4 or 6 may follow one below the other on the film band 2 to form a column.

Fig. 2 shows a letterpress unit carrier 2 with gauge holes 3 arranged in one continuous line along one edge thereof. If each unit 1 be, for 40 instance, adjusted in position in such a manner that the adjacent three holes 3 are engaged at the same time by three pins 5 and if the pins 5 extend accurately in alignment in the direction of the column length, the geometrical position 45 of the particular unit 1 will be perfectly accurately defined. The compositor makes a mark 9 at the first line of the column and another mark 10 at the last line, so that he is always guided as to the setting out of the carrier 2, even before 50 the undeveloped line images become visible. Fig. 2 shows that at the beginning and end of the column of line units there is an empty line in each case so that it becomes possible to adjust both the first line and the last line by the associated three holes 3. The single-row marginal perforation is particularly suitable for narrow letterpress unit carriers and has the advantage that the feed mechanism for advancing the carrier during the reproduction will not require re-adjustment, even if the column width should vary 60 within certain limits. A further advantage is that the carrier can expand freely in the line direction.

Similar advantages are shown by the carrier 65 2 according to Fig. 3, which is provided with a double row of gauge holes 6 disposed along one margin thereof. In this case the two pins 7, which lie in the line direction, suffice for accurately adjusting and advancing the particular 70 unit 1, such carriers 2 being suitable for wider columns than those according to Fig. 2. From Fig. 3 it will be seen that it is not necessary to leave blank line spaces either at the beginning or at the end of the column. The pairs of holes 75

are so close together that any expansion in the transverse direction of the narrow film strip lying between them can have no detrimental effect.

The common carrier 2 according to Fig. 4 differs from that according to Fig. 3 mainly in this that the gauge holes 3, 4 are arranged in single rows along the two margins of the same. Such carriers 2, which are adapted for the greatest column widths that are likely to occur, are preferably initially perforated for the different column widths according to graded standard widths. The means provided on the reproduction apparatus for co-operation with one vertical row of perforations are made adjustable in accordance with the length of line, that is to say, the width of the column unit, so that carriers 2 of different widths can be fed forward with the same feed mechanism.

It will be seen from Figs. 2 to 4 that carriers 2 of a great variety of column widths have the same fixed line spacing owing to the standard size of type of the units with the same feed motion. Each feed movement brings only one line image into the projection gate of the reproducing apparatus which has to uncover nothing more than the particular line image in question. The single line feed allows of freedom in the photographic reproduction where, for instance, one line can be enlarged independently of the others, and does away with the danger of any irregularities which may occur being added to one another. The accuracy of the edges of the common carrier is of no importance in view of the locating of the lines by means of the gauge holes.

Rough proofs may be taken from the roughly set up columns on the carriers 2 by contact printing, in which there is sufficient space for indicating the corrections in the spaces between the lines. The lines to be corrected may be set up in a separate correction column which is placed in the reproduction position at the lines in question instead of the column on the carrier 2. If it should be preferred, however, to correct the continuous column on the carrier 2 itself, the lines to be corrected will have to be removed and replaced in any suitable way by the fresh lines.

Fig. 5 shows how a T-shaped piece 11 bearing a fresh line, which can of itself be adjusted in position, is inserted correctly in a carrier 2 of the kind shown in Fig. 2. The piece 11 is stuck to the rest of the carrier by means of the head part and, if necessary, also by means of the strip 12, the holes 3 remaining in position and the locating pins 5 acting normally. Larger fresh pieces 13 are inserted with transverse strips 14 and longitudinal strips 12 which are stuck to the emulsionless side of the carrier or to both sides thereof.

Fig. 6 shows the piecing together of a column carrier 2, such as that shown in Fig. 3. Single parts 15 and larger parts 13 which can be independently adjusted in position by means of their gauge holes are stuck on with the aid of strips 12 and 14. It is also possible to stick in larger surface 16 which, while they cover one or more line images, are nevertheless stuck together with an adhesive so transparent that they have no appreciable effect on the transparency of the line images in question. The strips and adhesive surfaces do not interfere with the gauge holes.

Fig. 7 shows the piecing together of a rough column carrier 2, such as that shown in Figure 4. The inserted pieces 15, 13 and the strips 14 are like those above described. H-shaped pieces 17

may also be inserted which can be stuck in without separate strips.

The piecing together is best carried out on a smooth table top 18, as shown in Figure 8, which is provided with sufficient positioning members 19 for enabling the fresh pieces and the original pieces to be accurately positioned with respect to one another. One or more positioning members 19 of the piecing table 18 are depressible and are spring-controlled at 20 in order to enable cutting 10 rulers to be placed on the rough column carrier 2 and to apply any suitable pressing means for smoothing the strips 14 and the like.

Fig. 9 shows how loose loops are left in the column carrier 2 which is advanced by the locating 15 pins or teeth 21 engaging in the gauge holes, before and after the guiding members 22, 23, in order that each separate adjustment of the same shall be affected only by the gauge holes 3 and the locating pins or teeth 21.

Fig. 10 shows a normal continuous column of letterpress units and Figs. 11 to 16 show how with such a column all sorts of type matter 24 can be set up by a purely photographic reproduction.

The length of the column is immaterial as regards the actual work, so that neither the piecing together nor the longitudinal expansion can have any effect. The latter could only have any effect for instance as regards one portion T, which however may be regarded as negligible in every 30 case.

The compositor can cut off the column carrier 2 by marks in any case and pass it on for development or any other treatment. As the column carrier is engaged mechanically only for single 35 line feed movements and for this purpose only by the gauging means of one single line, there will be no difficulty even with the shortest pieces as regards threading them into the feed mechanism and guiding them, any danger due to backlash 40 being fully provided for. The reduction in the waste of film and the columnar form itself render the wet photographic treatment of the units easy and cheap and what is of still greater importance is that by this means the machine 45 for the photographic setting up of the units is also made very simple and cheap.

Finally it may be remarked that as compared with the cinematographic film bands which are also preperforated (quite apart from the fact that 50 they are used for a totally different purpose and that the photographically produced matter can be freely set up in pages) there is this further fundamental difference that the position of the cinematographic images is independent of the perforations in the film, while according to the invention there is such a positive relationship 55 between the gauge holes and the rough column that the rough column can be corrected and accurately pieced together by the usual checking impressions 60 typed along with it, even immediately after exposure and before development.

I claim as my invention:

1. A photographic type composing process for producing the representation of the printing surface in its made up or page form which comprises photographically setting up step by step type matter in the form of lines or like letterpress units ready for reproduction directly on a common light-sensitive carrier in groups one below the other with a constant optional line spacing to form a roughly set up column, said common carrier being provided with gauging means arranged according to a system of two co-ordinates for each of the letterpress units for locating the letterpress 75

units accurately in correct relationship with respect to one another during their photographic reproduction, the said gauging means being arranged in alignment one below the other in the 5 direction of the one co-ordinate and being parallel to one another in the direction of the other co-ordinate.

2. The process as specified in claim 1, in which 10 said light-sensitive carrier is adjusted during the setting up of the letterpress units so as to bring the successive units into the exposure position only by the gauging means provided for each individual unit, said carrier being otherwise left relatively free.

15 3. The process as specified in claim 1, in which said carrier is adjusted during the setting up of the letterpress units so as to bring the successive units into exposure position only by the gauging means provided for each individual unit and in 20 which the letterpress units are normally set up on said carrier in a constant small size type and different sizes of type in the made up pages are obtained by varying the degree of enlargement when reproducing the units to form the page.

25 4. The process as specified in claim 1, in which said carrier, when in the reproducing position, is adjusted from one unit to another, in accordance

with the gauging means only provided for each individual unit, but is otherwise left relatively free.

5 5. The process as specified in claim 1, in which said carrier, when in the reproducing position, is adjusted from one unit to another in accordance with the gauging means only provided for each individual unit and in which said carrier is engaged unyieldingly by one of a pair of gauging means but is engaged by the other gauging means 10 so as to be capable of yielding in the direction of the common centre line of the pair of gauging means.

6. The process as specified in claim 1, in which 15 said carrier when in the reproducing position is adjusted from one unit to another in accordance with the gauging means only provided for each individual unit, and in which said carrier is engaged unyieldingly by one of a pair of gauging means but is engaged by the other gauging means 20 so as to be capable of yielding in the direction of the common center line of the pair of gauging means, the gauging means to be engaged in a yielding manner being subjected to the action of a spring-controlled member tending to spread the 25 gauging means apart and tension the carrier.

EDMOND UHER.
